(57) **CLAIM**

We claim the ornamental design for a vehicle, as shown and described.

DESCRIPTION

FIG. 1 is a perspective view of a vehicle showing our new design;

FIG. 2 is a front view thereof;

FIG. 3 is a right view thereof;

FIG. 4 is a left view thereof; and,

FIG. 5 is a top view thereof.

In the drawings, the broken lines shown in the Figures depict environmental subject matter only and form no part of the claimed design.

The portions of the vehicle not shown in the drawing form no part of the claimed design.

1 Claim, 5 Drawing Sheets
